UNITED STATES PATENT OFFICE.

HENRY L. HOOPENGARNER, OF SHIRLEY, WEST VIRGINIA.

WELL-DRILLING MACHINE.

No. 890,280.

Specification of Letters Patent.

Patented June 9, 1908.

Application filed April 20, 1907. Serial No. 369,317.

To all whom it may concern:

Be it known that I, HENRY L. HOOPEN-
GARNER, a citizen of the United States, residing
at Shirley, in the county of Tyler and
5 State of West Virginia, have invented cer-
tain new and useful Improvements in Well-
Drilling Machines, of which the following is a
specification.

This invention relates to machinery for
10 boring deep wells and for performing the
variety of work incident thereto, such as
spudding, baling and raising and lowering
tubing and casing, the machine being par-
ticularly designed for drilling, spudding and
15 baling or removing cuttings.

The invention has for its object to devise
a mechanism utilizing force derived from a
steam engine or other convenient type of
motor and comprising parts enabling such
20 force to be effectively directed and applied
according to the special needs of the work or
any exigency incident thereto such as spud-
ding, drawing tools from the well and the
like.

25 For a full description of the invention and
the merits thereof and also to acquire a
knowledge of the details of construction and
the means for effecting the result, reference
is to be had to the following description and
30 accompanying drawings.

While the invention may be adapted to
different forms and conditions by changes in
the structure and minor details without de-
parting from the spirit or essential features
35 thereof, still the preferred embodiment is
shown in the accompanying drawings, in
which:

Figure 1 is a side view of a well drilling
machine embodying the invention. Fig. 2
40 is a top plan view thereof. Fig. 3 is a detail
view of the main and spudding shafts show-
ing the connecting means. Fig. 4 is a detail
view of the main and power driven shafts
45 showing the brake coöperating with the
former and for transmitting motion to the
latter from the engine or motor. Fig. 5 is a
detail view of the sand reel shaft and the
brake or chock block coöperating with the
50 friction pulley fast thereto. Fig. 6 is a de-
tail view in perspective of a crank arm.
Fig. 7 is a detail view of the means for hold-
ing the operating rods in an adjusted pos-
ition.

Corresponding and like parts are referred
55 to in the following description and indicated

in all the views of the drawings by the same
reference characters.

The operating parts are mounted in a way
to admit of the machinery being readily
transported from place to place as occasion
60 may require. The frame-work for support-
ing such parts comprises longitudinal sills or
timbers 1 and transverse timbers or sills 2,
said parts being rigidly connected in any
substantial manner. The frame-work is 65
mounted upon ground wheels 3, the front
axle being arranged to turn in the manner
well understood to admit of proper steering
of the machine when moving it from one
70 place to another.

For imparting movement to the working
elements, an engine 4 of any type is mounted
upon one end of the frame-work and power
is transmitted from the shaft 5 thereof to the
main shaft 6 by means of drive belt 7 which 75
passes around band pulley 8 fast to shaft 5
and band pulley 9 fast to shaft 6. A pinion
10 is loose upon the shaft 6 and is provided
on one side with a half clutch 11 either
formed with or connected to said pinion so as 80
to turn therewith. A sleeve 12 is slidable
upon the shaft 6 and is connected thereto
by means of a feather and spline so as to ro-
tate therewith and is provided upon the end
facing the pinion 10 with a half clutch 13 85
matching the half clutch 11 so that when the
two half clutches 11 and 13 are in mesh, the
shaft 6 and pinion 10 will rotate together.
A shaft 14 arranged parallel to the shaft 6 is
journaled in bearings applied to the frame 90
work and carries a gear wheel 10^a adapted to
mesh with the pinion 10. When the clutch
sleeve 12 is moved away from the pinion 10
to unship the clutch members 11 and 13, the
shaft 6 will continue to rotate without im- 95
parting any movement to the shaft 14. The
shaft 14 is adapted to receive the rope, not
shown, by means of which the several tools
are operated. A brake wheel 15 is fast to an
end portion of the shaft 14 and coöperates 100
with a brake band 16 which is secured at one
end to a rod or bar 17 and has its opposite
end connected to the crank portion 18 of a
shaft 19 mounted in bearings applied to the
framework and having an operating handle 105
20. By proper manipulation of the handle
20, the brake band 16 may be caused to grip
the brake wheel 15 more or less tightly to
control the rotation of the shaft 14 and the
paying off of the operating rope or cable 110

wound thereon. When the shaft 14 is positively driven to wind up the rope as when drawing tools, casing or the like from the well, the brake band 16 is slack so as not to offer any resistance to the free rotation of the brake wheel 15 and shaft 14.

For operating the drill, a walking beam 21 is provided and mounted in bearings at the upper end of a post 22 rising from one side of the frame-work and suitably braced. One end of the walking beam 21 is adapted either to have the temper screw connected therewith or suitably supplied with means for operating the drill rope or cable. The opposite end of the walking beam is connected by pitman 23 with a crank 24 fast to the outer end of the shaft 6. The wrist pin 54 connecting the pitman 23 with the crank 24 is adjustable upon the crank to provide for varying the oscillation of the walking beam and the stroke of the drill, the said wrist pin being adapted to be inserted in a selected one of the openings 55. When drilling, the clutch sleeve 12 is moved to unship the clutch members 11 and 13 so as to impart no positive movement to the shaft 14. For moving the clutch sleeve 12, a shipper lever 25 is provided and fulcrumed at 26 upon a cross bar 27, a rod 28 connected to one end of the shipper lever extending within convenient reach to admit of ready operation of the shipper lever to throw the clutch in or out of gear as may be required.

The sand reel 29 is mounted upon a shaft 30 arranged transversely of the frame-work and parallel with the shafts 6 and 14, one end of the shaft being mounted in a bearing 31 applied to one side of the frame-work, and the opposite end portion of the shaft 30 being mounted in a lever 32 pivoted at 33 to the opposite side or sill of the frame-work. The shaft 30 is mounted to have a limited swinging movement with respect to the bearing 31, whereby the shaft may move with the lever 32 which is essential to control the movements of the shaft and the sand reel mounted thereon. A pulley 33^a fast to an end portion of the shaft 30 is adapted to make frictional contact with either band pulley 9 or a brake block 34 firmly attached to the sill 1 supporting the lever 32. When the lever 32 is moved in one direction to bring the pulley 33^a in engagement with the pulley 9, the shaft 30 is positively rotated to wind up the rope, not shown, upon the reel 29, thereby lifting the bucket commonly employed for baling the well or removing cuttings. Upon moving the lever 32 in the opposite direction, the pulley 33 may be brought into contact with the brake block 34 with a greater or less friction so as to control the descent of the baler or sand bucket into the well. For operating the lever 32, a rod 35 is employed and extends within convenient reach of the operator, said rod having an end portion 36 con-

nected thereto by means of a swivel joint 37 to admit of said end portion 36 being turned to accommodate itself to the hand of the operator as may be required. The end portion 36 of the rod 35 is formed with a series of teeth 38 which are adapted to be engaged by a pawl 39 mounted in a post 40^a through which the end portion 36 of the rod passes.

For spudding, a shaft 40 is mounted in bearings and arranged parallel with the shafts 30, 6, and 14 and is provided with a crank 41 whose wrist pin 42 is adapted to engage with the operating rope or cable, not shown, to impart a tugging movement thereto, whereby the fishing tool is reciprocated or jiggled in the well. A crank 43 is fast to the outer end of the shaft 40 and is adapted to be connected by means of pitman 44 with the crank 24 of shaft 6 after said crank 24 has been disconnected from the pitman 23. When the two cranks 24 and 43 are connected as shown in Fig. 3, motion is imparted from shaft 6 directly to shaft 40, the latter being oscillated to impart a corresponding oscillatory movement to the crank 41, whereby the spudding or jiggling of the tool in the well is accomplished. A snatch block 45 is provided at one end of the frame-work for the operating rope or cable to pass over during the spudding operation.

From the foregoing, it will be understood that the machine is adapted for the various operations incident to boring or drilling deep wells. When drilling, the walking beam 21 is connected to the crank 24 as indicated in Figs. 1 and 2, the pinion 10 being disconnected from the shaft 6 by unshipping of the clutch members 11 and 13 to permit the rope to unwind from the shaft 14. To draw the tool from the well, the rope is disconnected from the walking beam in the usual way and the pinion 10 is clutched to the shaft 6, thereby imparting positive movement to the shaft 14 upon which the rope is wound. When lowering the tool into the well, the pinion 10 is disconnected from the shaft 6 by throwing the clutch sleeve 12 away from the pinion 10, the descent of the tool being regulated by proper manipulation of the lever 20 to cause the brake band 16 to grip the brake pulley 15 more or less tightly. For spudding, the walking beam is disconnected from the crank 24 and the cranks 24 and 43 are connected by the pitman 44, it being understood that the crank 24 is considerably shorter than the crank 43 to admit of rotation of the crank 24 so as to impart an oscillatory movement to the crank 43. The rope after being engaged with the wrist pin 42 of the crank 41 and after being passed over the pulley of the snatch block 45 is alternately tugged upon and relaxed with the result of imparting the jiggling movement necessary for the spudding operation. The baler has its speed controlled when descending into the well by pressing

the pulley 33 against the brake block 34. When it is required to withdraw the baler from the well, the pulley 33 is pressed into contact with the pulley 9. When it is required to reverse the engine, as in drilling and raising and lowering casing, the same may be effected by means of a rod 46 which passes through the post 40 and is provided with a series of teeth 47 for coöperation with a pawl 48 similar in operation to the pawl 39.

A cord, not shown, extending from the throttle valve or lever of the engine is adapted to pass over or to be connected with a pulley 49. The several controlling devices are located within convenient reach of the operator from the most advantageous point as shown most clearly in Figs. 1 and 2. At or near the well is located a mast 50 which is of sectional construction for convenience of handling and storing, said mast being braced by suitable guys 51. A crown pulley 52 is provided at the outer end of the mast for the operating rope to pass over during the drilling and spudding operations. A second pulley 53 is provided near the top of the mast and at one side thereof for the sand rope to pass over.

Having thus described the invention, what is claimed as new is:

30 The herein-described well drilling machine comprising a frame-work, a transverse shaft 6 journaled thereon, a drive pulley 9 rigid with the shaft, a pinion 10 loose upon the shaft and provided with a half clutch 11, a sleeve 12 rotatable with the shaft and slidable thereon, the said sleeve being formed with a half clutch 13 matching the half clutch 11, a cross bar 27, a shipper lever 25 pivoted upon

the cross bar 27 and engaging the sleeve 12 to move the half clutch 13 into and out of engagement with the half clutch 11, a second shaft 14 disposed parallel to the shaft 6, a gearwheel 10^a mounted upon the shaft 14 and meshing with the pinion 10, a brake mechanism coöperating with the shaft 14, a post 22 45 projecting from the frame-work, a walking beam 21 mounted upon the post, a crank 24 rigid with the shaft 6, a pitman 23 for detachably connecting the crank 24 to the walking beam during the drilling operation, a shaft 40 50 journaled upon the frame-work parallel to the before mentioned shafts and provided with a crank 41 for spudding, a second crank 42 rigid with the shaft 40, a pitman 44 for connecting the cranks 43 and 24 during the 55 spudding operation, a fourth shaft 30 parallel to the before mentioned shafts and provided with a sand reel, one end of the shaft 30 being journaled in the frame-work while the opposite end is journaled in the lever 32, 60 a pulley 33^a upon the shaft 30, a brake block 34 mounted upon the frame-work on one side of the said pulley, means for operating the lever 32 on one end of the frame-work for throwing the pulley 33^a either into contact 65 with the brake block 34 or the pulley 9 upon the shaft 6, and a snatch block 45 at one end of the framework to receive the operating cable during the spudding operation.

In testimony whereof I affix my signature 70 in presence of two witnesses.

HENRY L. HOOPENGARNER. [L. S.]
